LIPSTICK DEVICE

James L. Younghusband, Chicago, Ill.

Original application May 4, 1942, Serial No. 441,750. Divided and this application March 10, 1943, Serial No. 478,618

3 Claims. (Cl. 206—56)

This is a divisional application from the original filed on May 4, 1942 under Serial No. 441,750 for Lipstick device, now Patent No. 2,314,261.

My invention relates to a device for holding lipstick, said device so constructed as to make the lipstick adjustably available as used for application by the user.

Among the objects of my invention is to create a simplified construction for the projection and retraction of a lipstick with relation to a case. To provide an adjustable construction which will permit the user to project a lipstick to the extent desired so that the same may be applied by the user free from any obstructing mechanism adjacent the projected lipstick and such other objects, advantages and capabilities as will later more fully appear and which are inherently possessed by my invention.

While I have shown in the accompanying drawing preferred embodiments of my invention, yet I wish it understood that the same are susceptible of modification and change without departing from the spirit of my invention.

Referring to the drawing, Fig. 1 is an elevational view of my lipstick device in closed position; Fig. 2 is an elevational view of my lipstick device with the cap removed; Fig. 3 is an enlarged longitudinal sectional view of Fig. 1; Fig. 4 is an enlarged longitudinal sectional view of Fig. 2; Fig. 5 is a sectional view of my cord passing through the control member with a knot therebelow; Fig. 6 is a detailed sectional view of my control member with corrugated walls and Fig. 7 is a longitudinal sectional view showing a side opening in the case.

The embodiment selected to illustrate my invention comprises a hollow body member 10 or case having side walls 11, a closed bottom 12 and an open top 13. A spring 14 is positioned within said body member 10, with the bottom portion of the spring 14 engaging the interior of the closed bottom 12. The upper portion of said spring 14 engages the bottom of a holder or cup 15. The cup 15 is slightly smaller in its dimensions than the hollow interior of body member 10, so as to permit vertical movement with respect thereto. Said cup 15 is adapted to hold a lipstick 16 or the like.

A cap or closure 17 for the open top 13 is provided, said cap adapted to be removably positioned by friction grip within depression 18 on the side walls 11 adjacent their upper ends.

A cord, chain or other length of material 19 is attached at or adjacent to one end to said cup 15 and extends downwardly through spring 14

and opening 20 in bottom 12 (or the side wall as shown in Fig. 7), thence to cap 17 to which it is attached at or adjacent its other end.

In my preferred form cord 19 has a knot 21 positioned in cup 15 and of a larger size than opening 22 in cup 15 through which cord 19 below knot 21 passes. Cord 19 may also have a knot 32 positioned in cap 17 beyond opening 23 therein.

When the device is in closed position, with cap 17 covering the open top 13, cord 19 extends horizontally across the balance of the cap 17 to one of the side walls 11 and then vertically along said side walls to the outside of bottom 12 where it extends horizontally until it enters opening 20 thence vertically to cup 15.

A control member 24 which may be in the shape of a ball, bead or any other suitable form is carried on cord 19, below closed bottom 12. My control member 24 has an opening 25 therethrough.

The desired embodiment of my invention provides that the cord 19 extend through opening 25 with cord 19 of sufficient thickness and opening 25 of such corresponding dimensions that cord 19 engages walls 28 surrounding opening 25.

Frictional engagement between cord 19 and walls 28 is thus effected which is not overcome by the action of spring 14 pulling cord 19 and forcing control member 24 against bottom 12. The frictional engagement is such that it may not be overcome by pressure greater than that of spring 14.

The control member, of course, would be so positioned on cord 19 originally as to permit but a slight projection of the lipstick. Later the user by applying sufficient pressure to control member moves control member downwardly on cord 19 providing a greater length of cord between the control member and the cup and permitting greater projection of the lipstick. A knot 29 may be formed in cord 19 at a desired lower place thereon to stop control member from being moved therebelow and prevent so much cord above the control member as to permit ejection of the cup 15 and also to prevent the control member from contacting cap 17.

In order to promote greater frictional contact I may provide my walls 28 with corrugations 30 opposite to the plane of the cord or provide walls 28 with roughened surfaces, to engage the strands of the cord 19.

After use of the lipstick the user in moving cap 17 to be placed on open top 13 in closed position, pulls cord 19 so that cup 15 is forced against the action of spring 14 back into the interior of the body member 10.

With my invention the user does not have to

have the entire length of lipstick projected at the outset. Such a length would incur the likelihood of being broken off. By projecting only portions of the lipstick as needed, breakage is prevented, waste is saved and better application surface is provided.

Having thus described my invention, I claim:

1. A lipstick device comprising a hollow case having an open top, a bottom and an opening adjacent its lower portion, a holder adapted to hold lipstick movable within said case, a closure adapted to removably close said open top, a spring positioned between the bottom of said holder and the bottom of said case, a control member having an opening therethrough, a cord attached on one end to said closure, and extending from said closure through said opening in said control member, then passing through said opening in said case and attached at its other end to said holder, said control member positioned on said cord below said case, said cord of sufficient thickness and the walls surrounding the opening of said control member of corresponding dimensions so that said cord engages said walls and remains in fixed position with respect thereto by frictional contact, said control member originally positioned on said cord so that the length of cord between said control member and said holder permits the holder when the closure is removed and the holder is in receipt of upward pressure from said spring to move so that only a limited portion of the lipstick is exposed for application, said control member being slideable downwardly on said cord upon receipt of downward pressure thereon by the user greater than the pressure of said spring so as to provide greater lengths of said cord between said control member and said holder to permit greater upward movement of the spring actuated holder and correspondingly greater exposures of said lipstick, said cord adapted upon pressure from the user to pull said holder with its lipstick against the action of the spring back into said case, said cord of sufficient length to permit said closure to be removably positioned to cover said open top.

2. A lipstick device comprising a hollow case having an open top, a bottom and an opening adjacent its lower portion, a holder adapted to hold lipstick movable within said case, a closure adapted to removably close said open top, a spring positioned between the bottom of said holder and the bottom of said case, a control member having an opening therethrough, a cord attached on one end to said closure, and extending from said closure through said opening in said control member, then passing through said opening in said case and attached at its other end to said holder, said control member positioned on said cord below said case, said cord of sufficient thickness and the walls surrounding the opening of said control member of corresponding dimensions so that said cord engages said walls and remains in fixed position with respect thereto by frictional contact, said control member originally positioned on said cord so that the length of cord between said con-

trol member and said holder permits the holder when the closure is removed and the holder is in receipt of upward pressure from said spring to move so that only a limited portion of the lipstick is exposed for application, said control member being slideable downwardly on said cord upon receipt of downward pressure thereon by the user greater than the pressure of said spring so as to provide greater lengths of said cord between said control member and said holder to permit greater upward movement of the spring actuated holder and correspondingly greater exposures of said lipstick, said cord having stop means positioned below said control member to stop said control member from movement therebelow, thereby preventing a sufficient length of cord above said control member to permit ejection of said cup from said case, said cord adapted upon pressure from the user to pull said holder with its lipstick against the action of the spring back into said case, said cord of sufficient length to permit said closure to be removably positioned to cover said open top.

3. A lipstick device comprising a hollow case having an open top, a bottom and an opening adjacent its lower portion, a holder adapted to hold lipstick movable within said case, a closure adapted to removably close said open top, a spring positioned between the bottom of said holder and the bottom of said case, a control member having an opening therethrough, and corrugations on the inner walls surrounding said opening, a cord formed of strands, said cord attached on one end to said closure, and extending from said closure through said opening in said control member, then passing through said opening in said case and attached at its other end to said holder, said control member positioned on said cord below said case, said cord of sufficient thickness and the walls surrounding the opening of said control member of corresponding dimensions so that the strands of said cord engage the corrugations of said walls and said cord remains in fixed position with respect thereto by frictional contact, said control member originally positioned on said cord so that the length of cord between said control member and said holder permits the holder when the closure is removed and the holder is in receipt of upward pressure from said spring to move so that only a limited portion of the lipstick is exposed for application, said control member being slideable downwardly on said cord upon receipt of downward pressure thereon by the user greater than the pressure of said spring so as to provide greater lengths of said cord between said control member and said holder to permit greater upward movement of the spring actuated holder and correspondingly greater exposures of said lipstick, said cord adapted upon pressure from the user to pull said holder with its lipstick against the action of the spring back into said case, said cord of sufficient length to permit said closure to be removably positioned to cover said open top.

65 JAMES L. YOUNGHUSBAND.
